AIR CONDITIONING FURNACE

Hart H. McNaughton, Maryville, Tenn.

Application April 24, 1939, Serial No. 269,802

11 Claims. (Cl. 126—99)

This invention relates to an improvement in air conditioning furnaces designed for heating or cooling the air to be circulated in a room or building.

The object of the invention is to assemble a plurality of units into an air conditioning plant or heater so as to utilize units of standard construction which may be individually regulated and assembled at the place of manufacture, and yet may be shipped to and assembled at the point of use or installation. This enables the construction of an air conditioning furnace or plant in an inexpensive manner and with substantial economy both as to construction and installation.

A further object of the invention is to improve the supply of air both to the heating chamber and to the combustion chamber, as well as the regulation thereof, by utilizing a single blower for supplying air to both chambers under the control of suitable regulating vanes which direct air to the combustion chamber according to the extent of operation of the burning unit, discontinuing or diminishing this supply when the burning unit is not operating or is functioning to a very slow extent only. In this way, the regulating vanes act automatically to control the air for combustion and act as a safety device to prevent undue heat from excessive air according to the amount or character of the fuel supplied.

I have illustrated a preferred embodiment of my invention in the accompanying drawings in which:

Fig. 1 is a perspective view of the assembled air conditioning furnace;

Fig. 2 is a vertical sectional view therethrough, substantially on the line 2—2 of Fig. 3;

Fig. 3 is a horizontal sectional view therethrough, substantially on the line 3—3 of Fig. 2;

Fig. 4 is a horizontal sectional view through the lower portion of the furnace showing the stoker drive and control mechanism, substantially on the line 4—4 of Fig. 2;

Fig. 5 is a detailed side elevation, partly in section, showing the speed change belt;

Fig. 6 is a transverse sectional view therethrough on the line 6—6 of Fig. 5;

Fig. 7 is an enlarged side elevation of the driving mechanism and controls, parts being in section;

Fig. 8 is a detailed side elevation of the air regulating valve detached;

Fig. 9 is a similar view of the automatic control vane;

Fig. 10 is a detailed end elevation of a portion of the stoker and its driving mechanism;

Fig. 11 is a detailed cross section and elevation of a portion of the control box and its contacts;

Fig. 12 is an enlarged sectional view through the lower portion of the stoker;

Fig. 13 is a similar view through the upper portion of the stoker; and

Fig. 14 is a partial sectional view therethrough on the line 14—14 of Fig. 13, with parts in plan.

This improved air conditioning furnace is designed for use in the usual manner of hot air furnaces by drawing air through the cold air system of the house into and through the furnace where it is warmed or cooled, as desired, filtered and humidified, and then recirculated through the ducts back to the various rooms of the house or other portions of the building in which the furnace may be used.

Fig. 1 shows the various units comprising the complete furnace or plant assembled in compact arrangement. As here shown, the numeral 1 designates the chassis which encloses all of the operating parts of the furnace where they may be assembled and adjusted in the shop ready for transportation to the desired point of use. The chassis 1 and the other structural parts of the respective units are preferably formed from sheet metal, braced with the usual angles to add strength where needed for securely enclosing the operating parts therein and to permit of proper assembly.

Mounted upon the chassis 1 is a heating chamber 2, the construction of which may be similar to that usually provided in a furnace of this character, except that it has a door 3 in one side thereof to provide access to the interior of the heating chamber for cleaning or repairs and through which the heating unit may be installed or removed. A clinker door 4 is provided within the door 3 for removing the clinkers from the stoker unit, and said clinker door 4 serves also as an opening through which the fire pot may be relined without removing the heating unit from the heating chamber.

The heating chamber 2 rests upon the chassis 1 and is in substantial communication therewith, which lets the air recirculate in contact with all warm parts of the heating unit, as shown in Fig. 2. To confine the noise of the working parts of the furnace that are enclosed within the chassis, the walls of the heating chamber 2 are lined with noise deadening pads on shields

5, which also line the top 6 of the heating chamber.

All operating parts of the furnace are mounted preferably on rubber pads or springs that reduce vibration and noise, as will be described hereafter. The bottom of the chassis 1 is covered with an asbestos lining 7 (Fig. 2) to confine the heat within the furnace at this point and to prevent the danger of fire.

The chassis 1 is provided with an opening 8 into the bottom of the air chamber of the stoker through which the stoker may be cleaned out at this point and any ash or other foreign matter removed. A second door 9 in a side of the chassis 1 provides an opening to the moving parts of the mechanism for gaining access thereto.

The heating chamber 2 is preferably provided with a humidifier 10 of usual construction and may be automatic if desired. The upper portion of the heating chamber 2 has outlets 11 adapted for communication with the warm air conduits leading to the respective rooms or other parts of the building.

Extending transversely in the top of the chassis 1 are angle bar supports 12 upon which is supported a combustion chamber 13, which may be either round or square, and the top and bottom thereof may be welded or otherwise secured. The combustion chamber 13 has a lateral opening 14 in a side thereof extending to the door 4, while the opposite side has a flue vent 15 for connection with the chimney.

Mounted within the combustion chamber 13 and supported upon the bottom thereof is a fire pot 16 preferably lined with fire bricks 17. The fire pot 16 extends upwardly within the combustion chamber 13, as shown in Figs. 2 and 3. As shown in Figs. 13 and 14, the combustion chamber 13 and fire pot 16 are held in place on the angle bars 12 by clamps 18, one end of each engaging under an angle bar 12, while the opposite end is connected by a bolt 19 with a lug 20, extending laterally from a side wall of the combustion chamber 13. Thus, the combustion chamber is locked in place on its supports for easy removal or ready assembly, as desired.

Mounted directly in the bottom of the fire pot 16 is a tuyère head 21, as shown in Figs. 2 and 13, which head has radial openings 22 into the center thereof for directing air for supporting combustion. This tuyère head 21 may be assembled in the fire pot 16 in the shop as a unit, and then transported to the point of use for assembly in the furnace.

Coating with the tuyère head 21 and mounted in the chassis 1, is a fuel stoker having a bowl 23 located within the supporting bars 12, as shown in Fig. 12. The bowl 23 is provided with a surrounding flange 24 having openings 25 therein for the supply of air upward therethrough to the radial tuyère openings 22. A lip 26 on the upper edge of the bowl 23 is received within the groove 27 in the head 21 to form a tight connection therebetween and to prevent the leakage of dust and air. The chassis 1 is provided with an air chamber 28 therein enclosed by a surrounding wall 29, to supply air through the openings 25 and the tuyères 22 to support combustion.

The stoker is shown as of the usual screw type, having a tube 30 extending to the bowl 23 from a chute 31 and supported at its outer end on resilient mountings 65. Upon the outer end of said chute is seated a hopper 32 in communication therewith, as shown in Fig. 2. The tube 30 receives a conveyor screw 33 operatively mounted

therein and having a shaft 34 journaled in one end of the tube 30 and projecting therefrom, carrying a sprocket wheel 35, as shown in Figs. 2, 10 and 12.

5 The sprocket wheel 35 is connected through a sprocket chain 36 with a sprocket wheel 37 mounted on a shaft 38 (Figs. 4 and 10) journaled at one end in the chassis 1.

The opposite end of the shaft 38 from the sprocket 37 is mounted in spaced bearings 39 (Fig. 4) which bearings are supported on a base 40. The base 40 also carries anti-friction bearings 41 in which a shaft 42 is journaled. The shaft 42 carries a worm or spiral gear 43 thereon meshing with a worm wheel or coacting spiral gear 44 mounted upon and slidably keyed to the shaft 38, so as to be capable of longitudinal sliding movement relative thereto while maintaining its driving connection therewith.

10 The base 40 is slidably mounted upon rods 45, as shown in Fig. 6, which rods are shown as carried by angle bar supports 46. Thus the base 40 is capable of forward and backward adjustment on the rods 45, during which movement the gear 44 will slide along the shaft 38 and maintain the driving connection therewith.

15 The adjustment is accomplished by means of a lever 47 (Fig. 4), one end of which is forked and engages a pin 48 attached to the base 40, while the opposite end forms a handle for adjustment and projects through the external wall of the chassis as shown in Fig. 1. The lever 47 extends over a bracket 49 provided with a series of openings to receive a pin 50 which locks the lever in any one of several adjusted positions according to the desired location of the base 40.

20 The shaft 42 has mounted thereon opposed cones 51 and 52, the cone 51 being fixed to the shaft 42, while the cone 52 is slidably keyed to the shaft, being pressed toward the cone 51 by a coiled spring 53 interposed between the cone 52 and a collar 54.

25 Extending between the cones 51 and 52 and forming a driving connection therewith is a belt 55 having blocks 56 secured to opposite sides thereof, as shown in Figs. 5 and 6, and suitably spaced apart so that the belt will turn in a relatively small radius, and which blocks 56 extend to the outer edges of the belt to increase the thickness thereof at the edges where the belt contacts the inner faces of the cones 51 and 52 with a driving connection therebetween, as will be apparent from Fig. 4.

30 The opposite end of the belt 55 extends over a pulley 57 carried by a tube 58 which tube is mounted on anti-friction bearings 59 on a shaft 60. The shaft 60 is mounted in anti-friction bearings 61 in a standard 62 at one end and in anti-friction bearings 63, in a standard 64 at its opposite end. The standards 62 and 64 are supported upon the angle bars 46, as shown in Fig. 7, which angle bars are carried on soft rubber blocks or mountings 65.

35 One end of the shaft 60 projects through a side wall of the chassis 1 and carries a pulley 66 thereon receiving a belt 67 (Fig. 1), extending over a pulley 68 on the armature shaft of an electric motor 69 which is mounted beside the chassis. Thus, when the motor is operating continuously while it is energized, the shaft 60 will be driven. This shaft 60 is free to rotate relative to the pulley 57, but carries a clutch 70 fixed thereon in position to coact with a cone 71 formed at one end of the pulley 57. When the cone 71 is in frictional engagement with the clutch 70,

the pulley 57 will be driven from the shaft 60 and transmit its driving motion through the belt 55 to the cones 51 and 52, thus driving the shaft 42, and through the gears 43 and 44, and the shaft 38, this motion is transmitted to drive the conveyor screw 33 to feed fuel through the stoker to the combustion zone. It will be evident that the speed of rotation of the shafts 38 and 42 may be varied by adjustment of the base 40 forward or backward. When the base is moved backward away from the shaft 60 the belt 55 is drawn toward the center of the cones 51 and 52, providing a more direct drive therefor and for the shaft 42, changing the ratio and increasing the speed of the latter.

The spring 53 allows the cone 52 to move backward and forward to permit of this relative adjustment of the cones to accommodate for this adjustment of the belt.

When the cone 71 is shifted out of engagement with the clutch 70 to discontinue the driving of the stoker screw, a cone 72 at the opposite end of the pulley 57 is shifted into engagement with a brake 73 fixed to the standard 62, which holds the pulley 57 against rotation, even though the shaft 60 may continue to rotate.

The pulley 57 is shifted longitudinally of the shaft 60 by a clutch ring 14, which is engaged by a bell-crank yoke 15, the free end of which is pivoted at 16 to one end of a rod 11, the opposite end of which is connected with the plunger 18 of a solenoid 19. The rod 11 extends through a bracket 80, between which bracket and a collar on the rod is sleeved a spiral spring 81, normally tending to urge the rod forwardly to move the cone 72 into engagement with the brake 73. The solenoid 19 is adapted to be connected through wires 82 with a thermostat located at a desired point to be energized when additional heat is required, for moving the rod 11 forward in Fig. 4 and shifting the pulley 57 to engage the clutch 70 and drive the stoker screw to feed additional fuel to the combustion area.

The shaft 60 also carries the rotor 83 of a sirocco blower within a blower casing 84, communicating at its discharge side with the interior of the chassis and the heating chamber 2 for directing air therethrough around the combustion chamber 13. The intake of the blower casing 84 communicates with a casing 85, one side of which is provided with an intake pipe 86 connected with the cold air conduit system 81, extending from the rooms or other parts of the house or building. Filters 88 of standard or well-known construction extend transversely of the intake casing 85 through which the air passes to the blower 83. The casing 85 is provided with a door 89 in one side thereof to facilitate examination or replacement of the filters 88.

Mounted over the casing 85 is a cooling unit 90 having provision for cooling the air passing through the conduit system in warm weather, as during the summer. The unit 90 is shown as provided with a door 91 for gaining access to the interior thereof. This cooling unit 90 may be of any suitable or well-known construction providing for refrigeration, but is shown as provided with water evaporator pans 92, as a means of cooling and humidifying the air passing therethrough. A damper 93 is adjustably mounted in the casing 85 having its respective edges slidably mounted in grooves 94 and 95 for adjustment from the full line position in Fig. 2 to the dotted line position therein. When located in the full line position, the damper 93 directs the incom-

ing air from the intake 86 into and through the cooling unit 90, thence downward beyond the damper through the casing 85 and the filters 88 to the blower 83. However, for winter use, the damper would be adjusted to the dotted line position in Fig. 2 for directing the air from the intake 86 downward to the blower.

As shown in Fig. 4, the discharge side of the blower 83 is not in direct communication with the air chamber 28 that supplies the air to support combustion in the stoker, but an opening is arranged therebetween controlled by a vane 96 pivoted at 97, to a wall 29 of the air chamber 28. The vane 96 is pivotally connected with a connecting rod 98, which extends to one arm of a bell-crank lever 99 pivoted at 100 to an extended portion of the base 40. The other arm of the bell-crank lever 99 extends into the path of an abutment 101 carried by the rod 77 in position to be actuated thereby upon energizing of the solenoid 79. The vane 96 is adapted for movement by the solenoid through the connections mentioned from the full line position in Fig. 4 to the dotted line positions therein, according to the adjustment of the support 40. When thus opened, the vane 96 deflects a portion of the air from the blower 83 into the air chamber 28 to support combustion at the tuyères 22. It will be noted that the vane 96 will be thus opened whenever the solenoid 79 is energized by its control thermostat to maintain a driving connection at the clutch 70 for driving the stoker screw. This saves the cost of an extra blower and motor for the stoker and also simplifies the structure with marked economies of construction and installation. It will be noted that when the base 40 is retracted to its dotted line position in Fig. 4, this provides for greater swinging movement of the bell-crank lever 99, pushing the vane 96 open further to the extreme dotted line position indicated in Fig. 4, thereby providing for the supply of more air to the chamber 28 to support combustion, according to the increased speed of the stoker feed which will be provided upon such adjusted position of the base.

In the passage of the air from the blower to the air chamber 28 is an inwardly projecting wall abutment 102 which directs the air from the blower laterally of said passage against a second vane 103 pivoted at 104 for swinging movement to the dotted line position in Fig. 4. The purpose of the secondary vane 103 is to control automatically the volume of air supplied through the passage to the air chamber 28 in addition to the control provided by the adjustment of the vane 96. This is desirable when the fuel becomes thin and furnishes less resistance to the air current when it might burn the tuyère castings. To reduce the quantity of air upon this increase in the velocity, the vane 103 will be forced back thereby from its full line position to its dotted line position in Fig. 4, which turns an angular portion 105 formed at the end thereof laterally into the air passage, thereby reducing the size of the passage and the amount of air supplied therethrough to the air chamber 28. A spring 106 bears against the back side of the secondary vane 103 to counteract the pressure of the air thereagainst. This secondary vane automatically controls the velocity by one moving part of the air for combustion, and acts as a safety device to prevent undue heat which would be caused by excessive air when there is less resistance by the fuel supply.

Also mounted on the chassis 1 is an electric

control box 107 in which the various standard controls are mounted to enable these to be assembled in the shop in position for ready adjustment merely by fitting the control box thereon through the use of contact switches 108, as shown in Fig. 11.

It will be clear that a thermostatic control will be provided in the room or building for controlling the operation of the electric motor 59 according to the temperature desired, and as indicated above, a separate thermostatic control set at a slightly lower temperature is provided in the same room for controlling the energizing of the solenoid 79.

To enable the heating unit to supply hot water for the house at all times, a standard automatic hot water heater 109 is provided as a part of the unit and mounted upon the chassis 1, as shown in Figs. 2 and 3. This hot water heater 109 has connections 110 and 111 for the respective hot and cold water lines of the building. The details of the heater structure are not shown since these may be of any suitable form, and may use electric or gas heating means for heating the same independently of the furnace. However, pipes 112 and 113 connect the heater with the interior of the heating chamber 13 which may be provided with a heating coil therein for this purpose, as is customary in furnaces. During operation of the furnace this will maintain a heated condition of the water in the heater 109, and when this is reduced, provision may be made for automatically heating the water by its individual heater.

I claim:

1. A heater comprising a heating chamber, a combustion chamber arranged in heat exchange relation therewith, a burner within the combustion chamber, a power stoker arranged to supply fuel to the burner and having a shaft for operating said stoker, means for supplying air to the heating chamber including a blower fan, and an air passage leading therefrom to the heating chamber, a shaft for driving said fan, power means for driving the last-mentioned shaft, change speed mechanism between the fan shaft and the stoker shaft and forming a driving connection therebetween to drive the stoker shaft from the fan shaft at variable speeds relative thereto, an auxiliary air passage leading from the first-mentioned passage to the combustion chamber, a deflector arranged to control the supply of air from the first-mentioned air passage to the auxiliary air passage, means for opening said deflector automatically when the stoker shaft is driven from the fan shaft, and means for varying the extent of opening of the deflector in response to variations in the speed of drive of the stoker shaft.

2. An air conditioning heater comprising a chassis having means forming a chamber therein and a top supporting frame, heating means mounted in the chassis chamber, a heating chamber separate from the chassis and mounted on the top supporting frame, a combustion chamber separate from the chassis and mounted on the top supporting frame thereof in enclosing relation around the heating means, and means for securing said chambers to the top supporting frame of the chassis.

3. An air conditioning heater comprising a chassis having means forming a chamber therein and a top supporting frame, heating means mounted in the chassis chamber, a heating chamber separate from the chassis and mounted on

the top supporting frame, a combustion chamber separate from the chassis and mounted on the top supporting frame thereof in enclosing relation around the heating means, a support mounted on the chassis frame and having the heating chamber and the combustion chamber jointly supported thereby as a unit, and means for securing said support to the top supporting frame of the furnace.

4. An air conditioning heater comprising a chassis having means forming a chamber therein and a top supporting frame, heating means mounted in the chassis chamber, a heating chamber separate from the chassis and mounted on the top supporting frame, a combustion chamber separate from the chassis and mounted on the top supporting frame thereof in enclosing relation around the heating means, means for securing said chambers to the top supporting frame of the chassis, and an air supply unit mounted on the chassis, said air supply unit having means for directing air to the heating chamber.

5. A heater comprising a heating chamber, a separate combustion chamber, means for supplying air to the heating chamber including a power blower, a drive shaft for said blower, fuel supply means for the combustion chamber having a control shaft, means for operating said control shaft from the blower drive shaft, means movable to open and closed positions for deflecting air from said air supply means to the combustion chamber, and means for jointly controlling the operating means and the deflecting means for supplying air to the combustion chamber during feeding of fuel thereto.

6. A heater comprising a heating chamber, a separate combustion chamber, means for supplying air to the heating chamber including a power blower, a drive shaft for said blower, fuel supply means for the combustion chamber having a control shaft, clutch means for driving the control shaft from the blower drive shaft, means movable to open and closed positions for deflecting air from said air supply means to the combustion chamber, and means for jointly engaging the clutch means and opening the air deflecting means for supplying air to the combustion chamber during feeding of fuel thereto.

7. A heater comprising a heating chamber, a separate combustion chamber, means for supplying air to the heating chamber including a power blower, a drive shaft for said blower, fuel supply means for the combustion chamber having a control shaft, clutch means for driving the control shaft from the blower drive shaft, means movable to open and closed positions for deflecting air from said air supply means to the combustion chamber, electrically actuated means for engaging and disengaging the clutch means, and means for opening the air deflecting means upon engagement of the clutch means for supplying air to the combustion chamber during feeding of fuel thereto.

8. A heater comprising a heating chamber, a separate combustion chamber, means for supplying air to the heating chamber including a power blower, a drive shaft for said blower, fuel supply means for the combustion chamber having a control shaft, clutch means for driving the control shaft from the blower drive shaft, means movable to open and closed positions for deflecting air from said air supply means to the combustion chamber, a clutch shift rod arranged to engage and disengage the clutch means, electro-magnetic means for moving said shift rod and adapted

for actuation in response to temperature variations, and means operatively connected with the shift rod for opening the air deflecting means upon engagement of the clutch means for supplying air to the combustion chamber during feeding of fuel thereto.

9. In a heater having a blower and fuel supply means, the combination of a drive shaft for the blower, a control shaft for the fuel supply means, a clutch on the drive shaft, a belt having a driving connection with the clutch, relatively movable discs operatively connected with the control shaft and receiving the belt therebetween for varying the speed of the discs upon relative movement thereof toward and from each other, and mounting means for the discs movable lengthwise of the belt to vary the speed thereof.

10. An air conditioning heater comprising a chassis having means forming a chamber therein with a top supporting frame, heating means mounted in the chassis chamber, a heating chamber separate from the chassis and mounted on the top supporting frame, a combustion chamber separate from the chassis and mounted on the

top supporting frame thereof in enclosing relation around the heating means, said heating and combustion chambers having the lower ends thereof open to the first-mentioned chamber, and means for supplying air to said first-mentioned chamber for admission therefrom to the heating and combustion chambers.

11. In a heater having a combustion chamber and a burner therein, the combination of a power 10 stoker for supplying fuel to the burner and having a drive shaft therefor, power means for operating said drive shaft, an air passage for supplying air to said combustion chamber, a vane movable to open and closed positions in said air 15 passage for controlling the supply of air therethrough, means normally tending to move said vane to a closed position, a clutch for connecting the power means with the drive shaft, means for actuating said clutch to engaged and disengaged 20 positions, and means for connecting said actuating means with the vane and constructed for opening said vane when the clutch is moved to an engaged position.

HART H. McNAUGHTON.
